[57] CLAIM

The ornamental design for pictoral communication cards, as shown and described.

DESCRIPTION

FIG. 1 is a front elevational view of the pictoral communication cards of the present invention; and,

FIG. 2 is a left side elevational view of one of the pictoral communication cards FIG. 1, the right side elevational view being a mirror image therof.

The rear elevational and top and bottom plan view are flat and unornamented.
